ATRYS.

UNITED STATES PATENT OFFICE.

ERNEST L. PORTER, OF BOSTON, MASSACHUSETTS.

COLOR-HOLDER.

1,316,324.

Specification of Letters Patent. Patented Sept. 16, 1919.

Application filed June 24, 1919. Serial No. 306,510.

To all whom it may concern:

Be it known that I, ERNEST L. PORTER, a citizen of the United States, residing at Boston, in the county of Suffolk and State 5 of Massachusetts, have invented new and useful Improvements in Color-Holders, of which the following is a specification.

This invention is an improvement on the structure disclosed by U. S. Patent No. 10 692,040, dated January 28, 1902, said structure comprising an elongated trough formed with internal supporting ledges at its ends, a grated cover adapted to be supported by said ledges and having a relatively wide 15 roller-containing opening, and relatively narrow liquid-receiving openings between narrow transverse members, forming a grating, and a roller journaled in bearings on the cover, and adapted to be partially immersed in liquid contained in the trough, the cover being of angular form so that the portion in which the roller is journaled is depressed below the end portions of the cover to correspondingly depress the roller.

25 The present invention relates entirely to the construction of the grated cover and the roller bearings carried thereby, and is embodied in the improvements which I will now proceed to describe and claim.

30 Of the accompanying drawings forming a part of this specification,—

Figure 1 is a top plan view of a color holder embodying the invention.

Fig. 2 is a section on line 2—2 of Fig. 1.

35 Fig. 3 is a section on a larger scale, on line 3—3 of Fig. 1.

Fig. 4 is a fragmentary perspective view, showing a portion of one of the flanged longitudinal members hereinafter described.

40 Fig. 5 is a view similar to Fig. 4, the longitudinal member being bent.

Fig. 6 is a perspective view of the stay piece and the extension thereof, hereinafter described.

45 Fig. 7 is a view similar to Figs. 5 and 6, the stay piece being attached to the flange of the longitudinal member.

The same reference characters indicate the same parts in all of the figures.

50 In the drawings, 12 represents a trough adapted to hold a liquid dressing 13 for shoes, the trough being provided with internal ledges 14, adapted to support the grated roller-supporting cover hereinafter described, said cover being adapted to support a roller 15, partially immersed in the

liquid, the upper portion of the roller projecting through a relatively wide opening in the cover, so that when the roller is rotated, the liquid is carried thereby above the 60 cover, in position to be taken up by a sponge held by the operator, who manipulates the sponge to return any surplus liquid to the trough, and suitably apply the remaining liquid to the shoe, as fully described in the 65 above-mentioned patent.

In carrying out my invention, I construct the roller-carrying cover as next described. 16, 16 represent longitudinal sheet metal strips or members forming the opposite 70 edge portions of the cover, said members being provided with downwardly projecting flanges 17. The blank from which each member 16 and its flange 17 are formed, is provided with a slit 18, before the member 75 is bent to form the flange 17, said slit extending entirely across the flange, as shown by Fig. 4. The member 16 is then bent transversely on the dotted line 19, 19 (Fig. 5), thus imparting an angular form to the member 16, and separating the edges of the slit 18 to form an opening 18^a in the flange 17.

To the flange of each member 16 I attach, preferably by solder, a sheet metal stay piece 20 (Fig. 6), said stay piece covering 85 the opening 18^a and being attached to the flange 17 at opposite sides of said opening. The stay piece therefore rigidly connects the portions of the divided flange 17, and maintains the angular form of the longitudinal member 16. Each stay piece is extended and bent to form an ear 21, spaced from the acting portion of the stay piece by a neck 22, the ear 21 being provided with an aperture 23 forming a bearing for the shaft 95 24 of the roller 15.

As shown by Fig. 3, the ear 21 is secured to the longitudinal member 16 by a solder joint at 25. A reinforcing member 26 having an aperture 27, is soldered, or otherwise rigidly secured, to the inner side of the ear 21, the apertures of said ear and reinforcing member coinciding and forming an adequate bearing for the shaft 24.

The longitudinal members 16 are spaced 105 apart and rigidly connected by transverse members soldered at their end portions to the longitudinal members 16. Said transverse members include a relatively wide sheet metal member 28, having downwardly 110 projecting ears 29, a relatively narrow sheet metal member 30 having downwardly pro-

jecting ears 31, a relatively narrow sheet metal member 32 having a downwardly projecting ear 33, wire members 34 between the members 30 and 32, and a relatively narrow sheet metal member 35, forming one of the end portions of the cover and provided with a downwardly projecting flange 36.

The end flanges 29 and 36 rest removably on the trough ledges 14, the arrangement being such that the cover and roller are supported relatively to the trough as shown by Fig. 2. The transverse members 28 and 30 form opposite sides of an opening containing the upper portion of the roller 15. The transverse members 30, 32 and 34 form a grating over which a sponge supplied with liquid by the roller may be moved by the operator to force back into the trough any excess of liquid absorbed by the sponge.

The transverse members 32 and 35 are separated by a relatively wide opening 39, which is covered by a movable closure 40, composed of a flap of sheet metal hinged at 41 to the transverse member 35 and resting loosely on the transverse member 32.

It is customary at the end of a day's work to remove the above described cover from the trough and pour out the liquid and sediment remaining in the trough. It is also customary for the operator to deposit the dressing sponge in the trough, after the latter is emptied, thus providing for the safe storage of the sponge when it is not in use. The opening 39 and closure 40 enable the operator to remove the sponge before commencing the next day's work, and to charge the trough with liquid, without removing the entire cover, the closure 40 being raised as indicated by dotted lines, to permit the removal of the sponge and the insertion of the charge of liquid, and then lowered, as shown by full lines, to partially cover the trough.

It will be seen that the combination of the flanged longitudinal members 16, the flanges whereof are slotted, and the stay pieces 20 applied to the flanges after the bending of the longitudinal members, said stay pieces having extensions forming bearings for the roller shaft, provides a strong and durable construction maintaining the longitudinal

members in the form imparted thereto by the bending operation, and providing rigid bearings for the roller shaft.

I claim:

1. A grated roller-carrying cover for a color-holding trough, comprising two longitudinal sheet metal members forming opposite edge portions of the cover and having downwardly projecting flanges at their outer edges, said flanges being provided with transverse slits between their ends, and the longitudinal members being bent to impart an angular form thereto, and form openings in the flanges, sheet metal stay pieces united to the flanges at opposite sides of the openings therein, whereby the angular form of the longitudinal members is maintained, said stay pieces being extended from the flanges and bent to form ears spaced from the flanges and apertured to receive a roller shaft, and transverse members attached to and extending between the longitudinal members, said transverse members being spaced apart to form a relatively wide roller-containing opening and relatively narrow liquid-receiving openings.

2. A grated roller-carrying cover substantially as specified by claim 1, the apertured ears formed by the stay-piece extensions being provided with apertured reinforcing members, the apertures of which coincide with the apertures in the ears.

3. A grated roller-carrying cover for a color-holding trough, comprising longitudinal members forming the opposite edge portions of the cover, and provided with roller bearings, transverse members attached to and extending between the longitudinal members, said transverse members being spaced apart to form a relatively wide roller-containing opening, relatively narrow liquid-receiving openings, and another relatively wide sponge-receiving opening, and a movable closure for the last-mentioned opening, hinged to one of the transverse members and resting loosely on the adjacent transverse member.

In testimony whereof I have affixed my signature.

ERNEST L. PORTER.
